(57) **CLAIM**

The ornamental design for a base for a fence post, as shown and described.

DESCRIPTION

FIG. 1 is a perspective view of a base for a fence post incorporating my design.

FIG. 2 is a top plan view of the base for a fence post shown in FIG. 1, the bottom plan view being a mirror image;

FIG. 3 is a front elevation view of the base for a fence post shown in FIG. 1, the rear elevation view being a mirror image; and,

FIG. 4 is a right-side elevation view of the base for a fence post shown in FIG. 1, the left side elevation view being a mirror image.
